UNITED STATES PATENT OFFICE

162,300

COMBINATION ELECTRIC LAMP FIXTURE
AND HOUSING FOR DOOR OPENING AND
CLOSING MECHANISM

George H. Hansen, Jr., Kansas City, Kans., assignor to The Vendo Company, Kansas City, Mo., a corporation of Missouri

Application January 16, 1950, Serial No. 7,268

Term of patent 7 years

(Cl. D10—7)

To all whom it may concern:

Be it known that I, George H. Hansen, Jr., a citizen of the United States, residing at Kansas City, in the county of Johnson and State of Kansas, have invented a new, original, and ornamental Design for a Combination Electric Lamp Fixture and Housing for Door Opening and Closing Mechanism, of which the following is a specification, reference being had to the accompanying drawing, forming a part thereof.

Fig. 1 is a plan view of a combination electric lamp fixture and housing for door opening and closing mechanism, showing my new design.

Fig. 2 is a side elevational view thereof.

Fig. 3 is an end elevational view thereof.

Fig. 4 is an elevational view of the end opposite to that shown in Fig. 3.

Fig. 5 is a fragmentary, sectional view taken on line V—V of Fig. 2; and

Fig. 6 is a fragmentary, sectional view taken on line VI—VI of Fig. 2.

I claim:

The ornamental design for a combination electric lamp fixture and housing for door opening and closing mechanism, as shown.

GEORGE H. HANSEN, JR.
